(57) **CLAIM**

The ornamental design for a latch handle, as shown and described.

DESCRIPTION

FIG. 1 is a first perspective view of a latch handle showing our new design attached to a grill.

FIG. 2 is a second perspective view of the latch handle showing our new design attached to the grill.

FIG. 3 is a third perspective view of the latch handle showing our new design.

FIG. 4 is a fourth perspective view of the latch handle showing our new design.

FIG. 5 is a front view of the latch handle showing our new design.

FIG. 6 is a back view of the latch handle showing our new design.

FIG. 7 is a first side view of the latch handle showing our new design.

FIG. 8 is a second side view of the latch handle showing our new design.

FIG. 9 is a top view of the latch handle showing our new design; and,

FIG. 10 is a bottom view of the latch handle showing our new design.

The broken lines shown in the Figures show environment and portions of the latch handle that form no part of the claimed design.

The shade lines in the Figures show contour and do not claim surface ornamentation or treatment.

1 Claim, 10 Drawing Sheets
